(57) **CLAIM**

I claim the ornamental design for a cutting head, as shown and described.

DESCRIPTION

The present application also relates to (1) U.S. design patent application Ser. No. 29/444,649, filed Feb. 1, 2013, titled “Cutting Head”; (2) U.S. design patent application Ser. No. 29/444,650, titled “Cutting Head”; (3) U.S. design patent application Ser. No. 29/520,686, filed Mar. 17, 2015, titled “Cutting Head”; and (4) U.S. design patent application Ser. No. 29/520,666, filed Mar. 17, 2015, titled “Cutting Head”. FIG. 1 is a left-front perspective view of the cutting head; FIG. 2 is a front view of the cutting head shown in FIG. 1; FIG. 3 is a rear view of the cutting head shown in FIG. 1; FIG. 4 is a left side view of the cutting head shown in FIG. 1;

FIG. 5 is a right side view of the cutting head shown in FIG. 1;

FIG. 6 is a top view of the cutting head shown in FIG. 1; and, FIG. 7 is a bottom view of the cutting head shown in FIG. 1.

The subject matter shown in dashed lines, and any surfaces of the design not shown, including interior surfaces, form no part of the claimed invention.

1 Claim, 7 Drawing Sheets
